UNITED STATES PATENT OFFICE.

THADDEUS FAIRBANKS, OF ST. JOHNSBURY, VERMONT.

FEED-WATER HEATER.

SPECIFICATION forming part of Letters Patent No. 336,802, dated February 23, 1886.

Application filed November 30, 1885. Serial No. 184,306. (No model.)

To all whom it may concern:

Be it known that I, THADDEUS FAIRBANKS, of St. Johnsbury, Caledonia county, in the State of Vermont, have invented a certain

5 new and useful Improvement relating to Feed-Water Heaters. It is intended more particularly for heating the feed-water of locomotive-engines; and I do hereby declare that the following is a full and exact description thereof.

10 I have devised a simple and convenient heater, which may be arranged immediately below the barrel of the boiler and parallel thereto, and in which the exhaust-steam is circulated through pipes with a degree of positiveness and vigor not ordinarily attainable, while the pipes are free to expand and contract, and the apparatus is capable of being easily applied together and taken apart to allow of examination, cleaning, and repairs.

15 The heating agent is the exhaust-steam. I use so much thereof as is necessary to effect the thorough heating of the water, the remainder being disposed of in any other ordinary or suitable manner. It is usually ejected 20 strongly up the chimney to promote the draft. I have not deemed it necessary to represent, and will not further describe, the provisions for obtaining the exhaust-steam. I will represent and describe it as received into my ap-

25 paratus through two pipes of sufficient caliber, one leading from the exhaust-pipe (not represented) on one side, and the other leading from the exhaust-pipe (not represented) on the other side, of the locomotive.

30 The following is a description of what I consider the best means of carrying out the invention. The accompanying drawings form a part of this specification.

35 Figure 1 is a central vertical section through my heater. A portion of the barrel of the boiler is shown in elevation. Fig. 2 is an elevation of the end which lies at the right hand in Fig. 1, and which, it will be understood, is toward the front of the locomotive. Fig. 3 is 40 a view of the inner face of the casting which applies on this end. Fig. 4 is a vertical section of a portion on the line $\alpha\alpha$ in Fig. 3. Fig. 45 5 is a horizontal section on the irregular line

yy in Fig. 2. Fig. 6 is a vertical section on the line zz in Fig. 1. Fig. 7 shows a modification. It is a central vertical section through the entire heater.

50 Similar letters of reference indicate corresponding parts in all the figures where they occur.

55 A is a cylindrical casing; A' the front end; A², the rear end, and A³ a partial horizontal partition.

60 B is an end casting, certain parts of which will be designated, when necessary, by additional marks, as B' B². It is peculiarly chambered. Its whole interior is filled by the exhaust-steam and the water produced by the condensation thereof. The arrangement provides for the easy and prompt discharge of the 65 water with a small quantity of the steam. The conditions maintain a lively circulation through the chambers in this casting, and through the connected pipes. The fresh exhaust-steam coming in through the pipes C is 70 received in chambers b. (See Figs. 1, 2, 4, and 5.) It thence flows through the orifices b* into the horizontal chambers b', and thence into the several pipes, which are immersed in the cold water in the heater.

75 D' D² are pipes leading from chambers b'. They receive each strong intermittent or pulsating currents of exhaust-steam in the direction indicated by the short thick arrows.

D are return-bends, and D² are pipes communicating between D and the chambers b².

80 The feed-water is received from the pump (not represented) through the pipe E', and traverses the whole length of the heater in contact with the lowermost tiers of the steam-heated pipes D' D². The partially-heated feed-water moves upward past the end of the partial partition A³, and traverses again the length of the heater in contact with the middle and uppermost tiers of pipes, D' D². It flows 85 out through the pipe E², raised to a temperature nearly up to that of the exhaust-steam, a little above 212° Fahrenheit.

90 G is a drip-pipe communicating with the chamber b', which extends up and down and 95 communicates through apertures b³ with the

chambers b^2 . The pipes $D' D^2$ are slightly inclined, as shown. The water of condensation moves by gravity and by the current of the steam through the pipes D^2 , chambers b^2 , and 5 holes b^3 into the contracted upright chamber b^4 , whence it escapes through the pipe G . There is a stop-cock or other provision, g , for varying the area of the passage of escape through the pipe G .

10 It is important not only to allow all the water of condensation to escape freely, but also a small quantity of uncondensed steam should so escape. This will insure that the apparatus does not become inefficient through the 15 presence of air instead of steam in the chambers.

A^4 are stout rings or frames, of wrought-iron, soft steel, or other suitable material, to afford strength to aid in producing a strong 20 tight connection of the casing A and the respective end plates, $A' A^2$. I propose to secure the rings A^4 to the cylinder A by rivets 25 A^5 , and then to attach the end plate A' at one end and the end plate A^2 and the casting B at the other end by bolts A^6 . The chamber b^4 is, for convenience of manufacture, made to open out into the open air through the upper end. The orifice is tapped and is afterward tightly closed by a screw-plug.

30 My invention makes an unusually reliable and efficient steam-heater, adapted to be supported by any suitable straps or frames close under the barrel of the boiler. The active circulation of the exhaust-steam through the 35 pipes, and the thorough presentation of the feed-water thereto allows it to serve with unusual efficiency. My heater is capable of raising the temperature of full feed from freezing to a point closely approximating the 40 temperature of the exhaust-steam, and without requiring to be so large as to add materially to the weight or cost of the locomotive. Its position under the barrel of the boiler makes it inconspicuous and does not in the 45 least interfere with the symmetrical appearance of the structure.

M is the lower portion of the barrel of the boiler. It will be understood that the boiler is of the ordinary form and arrangement of a locomotive-boiler, the barrel being level. My 50 heater is adapted to serve efficiently while lying parallel thereto and mounted close under it.

D^3 are single pipes extending nearly the whole 55 length of the interior of the latter. Each is in communication with a chamber, b' , and is divided through a good portion of its length by a horizontal partition. The steam can circulate in these pipes and be condensed and discharged 60 with some effect, but not nearly as efficiently as in the pipes $D' D^2$ and their connecting return-bends D , because the latter operate by a positive current of the steam. The reception of fresh exhaust-steam through the chamber 65 b' and the connection of the intermediate

chambers, b^2 , with the drip-passage insures a strong current moving backward through each pipe D' , downward through each return-bend D , and forward through each pipe D^2 .

I attach importance to the construction as 70 allowing the heater to extend horizontally under the boiler and in close proximity thereto, with assurance of active circulation of the steam through the structure.

In cold weather, and in first starting, the 75 stop-cock g in the pipe G should be liberally opened. When the apparatus is warmer, this may be partially closed. In lieu thereof or in conjunction therewith there may a cock or valve controlling the flow of the exhaust-steam 80 through each of the pipes C .

The end casting, B , is important in reinforcing and strengthening the adjacent end of the heater, which is greatly weakened by being bored to receive the pipes. It will be observed 85 that each of the partitions between the horizontal chambers $b' b^2$ presses directly against the end of the heater, and tends greatly to strengthen the weakened plate against the internal pressure to which it is subjected under 90 the strong action of the pump in forcing the water through this into the boiler.

Modifications may be made in the forms and proportions. I can use a greater or less number of the several pipes $D' D^2$ and their connecting bends D . There may be the same 95 number of tiers below as above the partition A^3 . The single pipes D^3 may be omitted. The horizontal partition A^3 may be varied in form.

Fig. 7 shows a modification in which a perforated pipe performs the function of the partition A^3 , compelling the current of water received through the pipe E' to traverse a great portion of the length of the heater and back again. I have shown the perforated pipe in 100 this figure as somewhat contracted in diameter at its open end. This induces such conditions that when the pump is working actively a large proportion keeps in the line of the axis of the pipe, and flows out at the extreme end; but other streams escape through the perforations. The conditions are favorable to the thorough heating of the whole. There may be circumstances under which this mode of distributing water into the heater 115 would be of advantage. For general use I prefer the forms and proportions substantially as shown in the previous figures.

I claim as my invention—

1. The casing $A A' A^2$, partial partition A^3 , 120 pipes $D' D^2$, and return-bends D , steam-connections C , drip-connection G , and water-connections $E' E^2$, combined and arranged to serve relatively to each other and to the barrel M of a locomotive, substantially as herein specified. 125

2. The casting B , having the steam-distributing chambers b , passages b^* , distributing-chambers b' , receiving-chambers b^2 , passages b^3 , and discharge-chambers b^4 , arranged 130 to serve relatively to the steam-pipes C , drip-

pipe G, pipes D' D², and provisions for circulating water in the spaces between, substantially as herein specified.

3. The horizontal casing A, steam end plate A', water end plate A², partial partition A³, ring A⁴, rivets A⁵, and bolts A⁶, in combination with each other, and with the end casting, B, return-bends D, pipes D' D², and pipes C G E' E², all arranged for joint operation, as to herein specified.

In testimony whereof I have hereunto set my hand, at St. Johnsbury, this 20th day of November, 1885, in the presence of two subscribing witnesses.
